CLAIM

We claim the ornamental design for a switch, as shown and described.

DESCRIPTION

FIG. 1 is a top perspective view of a switch showing our new design;

FIG. 2 is a bottom perspective view of a first side of the switch of FIG. 1;

FIG. 3 is a top perspective view of a second side of the switch of FIG. 1;

FIG. 4 is a bottom perspective view of a second side of the switch of FIG. 1;

FIG. 5 is a side elevation view of a first side of the switch of FIG. 1;

FIG. 6 is a top plan view of the switch of FIG. 1;

FIG. 7 is a side elevation of a second side of the switch of FIG. 1;

FIG. 8 is a bottom plan view of the switch of FIG. 1;

FIG. 9 is a side elevation view opposite the first side of the switch of FIG. 1; and,

FIG. 10 is a side elevation view opposite the first side of the switch of FIG. 1.

The broken lines in FIGS. 1 and 6 views show portion of the switch that form no part of the claimed design.
